ABSTRACT OF THE DISCLOSURE

A semiconductor substrate of one conductivity type having a diffused region of a second conductivity type circumscribed by an adjacent gold compensated intrinsic region.

This invention relates to semiconductor devices of the type especially suitable for use as fast operating switches and to the process for making such devices.

One major problem encountered in the design of a suitable switching device for computers is fulfilling the requirement of switching time without adversely affecting other parameters. In particular, if the capacity of a switching device, for example, a diode, is made sufficiently small by the use of a lightly graded junction and a small junction area, the lower limit of the transient response is set by the turn-off time (the time required to sweep out excess minority carriers above those present in the steady state "OFF" condition). The minimization of junction area and the use of a lightly graded junction, however, conflicts directly with the requirement that a switching device have a low forward-recovery voltage and approach as closely as possible the ideal DC voltage-current characteristics. These criteria imply a large area and a sharply graded junction. Thus, a series of design compromises are necessary if a useful switching device is to be realized.

A switching device may be viewed as a parallel circuit comprising capacitance (C_t) which is the depletion layer capacitance associated with the space charge region of a junction, and R_1 which is the impedance of a diode under conditions of reversed bias. A resistance R_s is in series with the parallel circuit and is dependent upon the semiconductor resistivity, diode geometry and contacts. For a relatively low capacitance, of the order of .5 pf., the junction area must be extremely small and the contact holes even smaller. The diffusion profiles must be shallow so that peripheral capacitance effects can be minimized. It can be shown for a diode capacitance per unit area of .06 pf. per mil square, the diffusion area is of the order of 1 mil and the contact hole is of the order .5 mil. Moreover, increasing the bulk resistivity in an attempt to lower the capacitance area is not advantageous since low doped P-type surfaces are very susceptible to inversion phenomena. Devices of the type described have been found to have capacitance of the order of 0.94 pf. whereas devices having capacitance of the order of .6 pf. are necessary for high speed switching operation.

A general object of the present invention is an improved semiconductor device structure which has low capacitance and forward recovery voltage and excellent reverse recovery characteristics.

2

Another object is a semiconductor switching device having a current dependency based upon the junction perimeter.

Another object is an improved semiconductor switching device which permits contacts to be larger than the active area of the device.

Another object is a semiconductor switching device having a diffused junction which presents minimum peripheral capacitance.

10 Another object is a semiconductor device having a PN-PIN junction.

Another object is a method of making an improved semiconductor device having low depletion capacitance and forward recovery voltage and good reverse recovery.

15 Another object is an improved method for making an ideal high beta switching element for information handling apparatus.

These and other objects are accomplished in accordance with the present invention, one illustrative embodiment of

20 which comprises epitaxially depositing on the surface of a P+ silicon substrate a relatively slightly doped (2.0 ohm-cm.) N-type material. An insulating layer, typically silicon dioxide is grown or otherwise formed on the surface of the epitaxial silicon. A conventional photolithographic operation is employed to establish islands of silicon dioxide on the surface of the wafer. The exposed N-type silicon is subjected to a highly doped P-type atmosphere (boron diffusion) to establish a P+ area in the openings. The diffused P+ area contacts the original

25 P+ crystal. The surface is reoxidized with silicon dioxide or the like and an opening is established in the oxide in a position over the N-type silicon. A phosphorous diffusion is conducted through the openings to cause the volume underneath to become highly N-type. The highly 30 N-type and P-type material form a junction which is bounded by an N-type region. The inverse side of the wafer is lapped and polished prior to the evaporation of approximately 100 Angstroms of gold on the surface thereof. The gold is diffused into the wafer at 1250° C.

35 for 20-25 minutes in nitrogen. After the gold diffusion, the wafer is cleaned with a polishing cloth and trichloroethylene. The gold diffusion compensates the low doped N-region and turns it into an intrinsic region. Additionally, the N+ and P+ regions establish an abrupt junction.

40 The resulting structure now has two distinct junctions. One is the normal P+N+ junction and the other is the P+IN+ junction. The P+N+ interface insures extremely 45 low forward recovery transient and a steep junction diode characteristic. The peripheral capacitance of the 50 device is negligible because of the wide intrinsic region which results in relatively low depletion capacitance of the order of 5. pf. The contact hole for the junction need not be contained in the junction area because of the intrinsic region.

55 One feature of the invention is that the current through the PIN junction is far greater than that through NP junction which renders the device current directly proportional to the junction perimeter rather than the area as in the case of prior art devices.

60 Another feature of the invention is that the voltage and field distributions in the intrinsic region are a function of the width of the intrinsic region W to the diffusion length L ratio and for the condition that W/L less than 1, the voltage drop in the intrinsic region is negligible.

65 Still another feature of the invention is employing a

W/L ratio of the order of 1 to permit the intrinsic region a good recovery time.

Still another feature of the invention is the use of a PN junction and a PIN junction where the transient current initially flows through the PN junction and as steady state current conditions are approached the PIN junction absorbs more and more of the current carrying capability until all of the current flows to the PIN junction.

The foregoing and other objects, features and advantages of the invention will be apparent from the following, more particular description of preferred embodiments of the invention as illustrated in the accompanying drawings.

In the drawings:

FIGURE 2 is a cross-sectional view of a semi-conductor device of the present invention.

FIGURE 2A is the device of FIGURE 2 with contacts added.

FIGURE 3 is a graph showing forward current versus applied voltage for the semiconductor device of the present invention.

FIGURE 4 is a graph showing the forward recovery voltage versus intrinsic layer thickness and gold doping density for the device of the present invention.

FIGURE 5 is a cross-sectional view of a transistor fabricated in accordance with the present invention.

Turning to FIGURE 1 a process for fabricating the semiconductor device of the present invention comprises a first operation 20 which involves the preparation of a single crystal silicon wafer having a P+ conductivity. Generally the wafer is prepared by taking a transverse slice from a single crystal of silicon produced in any one of a number of ways well known in the art. The doping of the wafer is of the order of 10^{19} atoms per ccm. where the dopant is taken from the group consisting of boron, aluminum, and gallium. The dopant is introduced into the silicon while in a melted state prior to a crystal pulling operation. The largest slice obtainable from the crystal after pulling will have a diameter of about 1 inch. The slice will have a resistivity of about .15 ohm cm. The slice is prepared for further processing by a conventional lapping and chemical cleaning technique so as to have two substantially parallel faces with a thickness therebetween of the order of .010 inch. From this slice a relatively large number of individual devices similar to that shown in FIGURE 2 are fabricated, as explained hereinafter.

As a second operation 22, an N type epitaxial layer of the order of 2 ohm-cm. is grown on the P+ silicon substrate. The silicon wafer is loaded on a carbon disc and placed in a deposition chamber which is flushed with nitrogen at a preselected rate and time. A hydrogen flush cleans the chamber of all nitrogen. The chamber is raised to 1140° C. and silicon tetrachloride is passed through hydrogen and enters the chamber. The dopant, typically phosphorous chloride (N-type), or the like in gaseous form, is also introduced into the chamber. A chemical reaction occurs in the chamber and elemental silicon doped with the N impurity is integrally grown on the wafer until a thickness of .25 mil is realized.

The next operation 24 involves the application of an oxidation film to the surface of the wafer followed by the etching of openings in the film. The oxidation of the film may be produced by thermal growth, evaporation or anodization. In thermal growth, for example, the wafer, disposed on a suitable carrier, is loaded into a quartz furnace which is adapted to admit dry oxygen and steam. The oxygen is permitted to flow after which steam is admitted instead of oxygen. The furnace is operated at a temperature of 970° C. while the steam and oxygen cycle last approximately 90 minutes. This interval permits thin oxide films of the order of 5500 angstroms thickness to develop on the wafer. The wafer is removed from the furnace and cooled for at least 15 minutes.

Afterwards a suitable photographic resistive material is applied to the surface thereof. The photoresist material may be any one of the compositions disclosed in Patents 2,670,285, 2,670,286, and 2,670,287 of Louis M. Minsk et al. Also a material sold by Eastman Kodak Co., Rochester, N.Y. under the trademark KPR (Kodak Photo-Resist) may be applied. Conventional methods of applying such a coating may be employed, such as brushing, dipping, spraying or the like which may be followed by a whirling operation to insure uniform and thin resist layers. It is important before applying the resist material to insure a clean surface by the use of suitable cleaning agents, for example benzol, toluene or like solvents. A pattern is photographically inscribed in the photoresist by well known means. The wafer is washed and suitably cleaned which eliminates the unexposed photoresist material. Thereafter, the wafer is subjected to an etchant which will attack the silicon dioxide coating, but leave unaffected the photoresist material. This leaves a bare silicon surface so that the portion exposed can later receive a suitable diffusion. One suitable etchant is a combination of ammonium fluoride (NH_4F) and hydrofluoric (HF) acid. Typically 10-30 parts of ammonium fluoride to 1-4 parts of hydrofluoric acid are combined depending upon the impurity desired to be diffused into the wafer. The etching interval is in the range from $5\frac{1}{2}$ to 8 minutes.

Afterwards, the wafers are removed from the solution and placed under distilled water for at least 30 seconds to 2 minutes. The clean surface is dried by air for approximately 30 seconds.

The oxidized wafer is now ready to receive a boron diffusion in an operation 26. A source of boron doped silicon, typically having a resistivity of the order of .0025 ohm cm., is loaded into a capsule with the wafer. The capsule is evacuated and sealed prior to a placement into a diffusion oven. The capsule is inserted into the center of the flat zone of the oven for 50 minutes. Thereafter, the capsule is removed and immediately quenched under running tap water. The wafers are removed from the capsule, after opening, and inspected for resistivity and junction profile. The boron diffusion results in the N-type regions under the openings being converted to P+ type conductivity. The diffusion time is selected to permit the P+ region to join the original P+ crystal. This time is the order of $4\frac{1}{2}$ hours for a furnace temperature of the order of 1175° C. The wafer is reoxidized in the manner described in the operation 24 after P+ boron diffusion.

Etching of suitable apertures in the reoxidized coating on the wafer occurs in operation 28. These openings are 0.6 or 0.8 mil diffusion holes using the standard photoresist techniques described in the operation 24. The 0.6 mil hole is open only if a 1.5 mil contact hole is planned to be used. A 0.8 mil hole is used only if a 0.6 mil contact hole is planned for a glass coating to be described hereinafter.

An operation 30 is subsequently performed which diffuses N-type material, typically phosphorus, into the openings in the oxide coating. A source of phosphorus pentoxide (P_2O_5) is loaded into a source boat and positioned in a three zone furnace. At the end of 30 minutes the source is pulled into a cold zone of the furnace (approximately 150° C). The wafers are loaded into a diffusion boat and inserted into the pre-heat zone of the furnace which is at approximately 850° . After the pre-heat cycle, the P_2O_5 source is returned to the 300° C. zone of the furnace and at the end of 10 minutes the diffusion boat is inserted into the 1000° zone of the furnace. A phosphorus diffusion occurs for approximately 8 minutes while the P_2O_5 source material is held at 300° for 5 minutes. After the 5 minute interval the source is pulled back into the cold zone. The phosphorous diffusion results in a junction depth of the order of $\frac{1}{10}$ of a mil. At the end of the diffusion time the wafers are

removed from the furnace and cooled, inspected prior to further processing.

A pre-gold diffusion operation 32 is performed where-in the inverse of the wafer is lapped and sandblasted. Typically, a wafer is blasted with a suitable grit until a uniform matte finish is observed. Any shiny areas are blasted again. The wafers are rinsed under distilled water and dried on a hot plate. A cleaning operation is performed by polishing both sides of the wafer with a mirror cloth and alcohol. To remove all visible wax, trichloroethylene or alcohol is applied to the surface of the wafer at room temperature for at least 1 minute. The wafers are dried prior to further processing.

A gold evaporation and drive-in operation 34 is performed to place a layer of gold on the inverse of each wafer. The gold is diffused in the wafer during a subsequent heating cycle. The evaporation is done in a conventional evaporator. The wafers are loaded into the bell jar which is placed under a vacuum of the order of 2.5×10^{-6} mm. of mercury. The evaporation takes place at 600° C. for a period of time sufficient to permit 100 angstroms of gold to be deposited on the wafer. The wafers are removed from the bell jar and readied for a gold diffusion which takes place in an oven. The oven is operated at a temperature of the order of 1250° C. for 20 minutes. The gold concentration is about 10^{15} to 10^{17} atoms per cubic centimeter. The gold serves a triple purpose. First, it introduces a large number of trapping centers into the silicon material which act as recombination centers and in such a way minimizes device storage time. Secondly, the gold compensates the low doped N region and turns it intrinsic. Thirdly, the time and temperature of the gold diffusion allow the N+ and P+ regions of the device to meet and form a junction.

After the gold diffusion a glassing operation 36 is performed. In one form, a glass mixture comprising 10 grams of a lead borosilicate glass with 30 ml. isopropyl alcohol is ultrasonically agitated for 10 minutes. After 24 hours soaking, an ethyl acetate is added and the mixture is ultrasonically agitated for 10 minutes. The mixture is centrifuged and the concentration reduced to .00205 gram per 10 cc. in an acetate solution. The concentration is poured into a container and the wafers added. The container is centrifuged at 3000 r.p.m. for 3 minutes to deposit uniformly the glass suspension on the wafers. The mixture is decanted and the wafers dried. The dried wafers are fired in a tube furnace at 1250° C. for 2 minutes. The glass coated wafers are removed from the furnace and cooled. Subsequently, the wafers are recoated with the same glass suspension to produce a final glass thickness of about 3.0 microns. Further details relative to the glassing are given in previously filed applications, Ser. Nos. 141,669, now abandoned and 141,668, now Patent No. 3,154,190 filed Sept. 29, 1961 and Sept. 29, 1961, respectively, and assigned to the same assignee as that of the present invention.

An etching operation 38 is next performed to establish contact holes through the glass and silicon dioxide to the silicon electrodes. As a first step, approximately 500 to 1000 angstroms of chromium are evaporated on the wafer at room temperature. A photoresist material is next applied to the deposit of chromium. The resist must be hydrofluoric resistant. One resist found to be suitable is Kodak Metal Etch Resist (KMER) a product of Eastman Kodak Co., Rochester, N.Y. The photoresist is deposited on the chromium by the technique described in the operation 28. A pattern is inscribed in the resist by well known photographic techniques. The wafer is cleaned to expose the metal. The exposed chromium is etched by a solution comprising approximately 20 grams of potassium ferric iron cyanide, $(K_3FE(CN)_6$) sodium hydroxide and water for $2\frac{1}{2}$ to 5 minutes depending on the thickness of the chromium. The exposed glass is etched in a solution comprising hydrofluoric acid. The etch is applied for approximately 60 seconds after which the

wafer is washed. A buffered HF etch is next applied to the wafer to dissolve the silicon dioxide and expose the silicon electrodes. The wafer is held in the buffered hydrofluoric acid for about 6 minutes. Following washing, the wafer is ready to receive contact metals.

5 is ready to receive contact metals.

10 The metal contacts are placed on the device in an operation 40. Following the etching operation, gold or palladium is evaporated at about 200° C. to a thickness of 6000 Å. The metal etch resist is removed by a hot trichloroethylene solution prior to further processing. Gold or palladium peels off with the photo resist remaining only in exposed silicon holes. The chromium is exposed on the surface of the wafer along with the gold or platinum. The gold is alloyed at around 400° C. for 5 minutes

15 15 A series of metals are deposited on the chromium to complete the contact metallurgy. Chromium, copper and gold evaporation are successively made through a mask to the wafer. The evaporator is a conventional construction. In one form, a 210 mgr. chromium charge is displaced on

20 20 tungsten strips of the evaporator. 850 mgr. of copper and 460 mgr. of gold are placed in the front and rear boats. The evaporator is pumped down to 5×10^{-6} mm. pressure. The wafers are heated at 180°. The copper is outgased by raising the temperature to the melting point.

25 25 75% of the chromium charge is evaporated first. The copper evaporation starts to overlap the chromium. The gold is evaporated to complete the evaporation. The chromium deposit has a thickness of the order of 1500 angstroms and establishes a glass-metal seal thereby completing the encapsulation of the junction and the devices.

30 30 The copper and gold deposits have thicknesses of the order 5000 angstroms each. The copper and gold metals permit solderable metals to adhere to the chromium sealing film.

35 The wafers are removed, from the evaporator, cooled and forwarded to a lead-tin evaporator. A lead-tin charge is placed in the evaporator. The wafers are loaded in the evaporator which is pumped down to 5×10^{-6} inches of mercury. The evaporation lasts 8-10 minutes and the low eutectic metal is alloyed to the gold-copper chromium film. No deposit occurs in the other areas of the wafers due to metal mask. The wafers are removed from the evaporator, cooled and separated from the metal mask. A lead-tin evaporation will enable a reflow joint to be established with a substrate. After inspection, the wafers are forwarded for cleaning in fluoroboric acid, hydrogen peroxide and distilled water to remove all the remaining traces of chromium, copper, gold, lead and tin. Subsequently, the wafer is diced into individual devices, one of which is shown in FIGURE 2.

The final device, shown in FIGURE 2, resulting from the process of FIGURE 1 comprises a wafer 50 having a silicon dioxide coating 52, and an N+ region 54 of approximately 0.6 mil width surrounded by an intrinsic region 58 of the order of 1.8 mils in total width. The N+ concentration is about 10^{21} atoms/cubic centimeter. The impurity concentration in the intrinsic region is about 10^{12} to 10^{13} atoms per cubic centimeter. The P+ concentration is 10^{19} atoms/cubic centimeter. A P+N+ junction 56 is established in the wafer at a depth of .18 mil from the upper surface thereof. An opening 62 is in the oxide coating. The intrinsic region 58 separates the sides of the N+ region 54 from the boron diffused region 60. The P+N+ region establishes a second junction 58' in the device. The interaction of junctions 56 and 58' results in a device that has high switching speed, low depletion capacitance, low reverse recovery and ideal DC voltage-current characteristics, for the reasons indicated in the remaining paragraphs. The device is further coated with a glass film 64, as shown in FIGURE 2A, to offset the hydrophilic characteristic of the film 52. A gold contact 53 covers the exposed region 54 and 58. A chromium film 66 covers the glass film 64 and the contact 53. Gold and copper films 70 and 68, respectively lay the foundation for a lead-tin contact 72.

The basis for the improved device operation is due in part to the current conditions in the device. It can be shown that two currents J_h and J_v (see FIGURE 2) flow in the device, the J_h current being horizontal and flowing in the PIN direction and the J_v being vertical and flowing through the $P+N+$ junction. Under conditions of forward bias, the vertical current J_v is as follows:

$$J_v = \frac{qD_n n_i^2}{L_n P} e^{\beta V} \quad (1)$$

where J_v =vertical current, q =electronic charge, D_n =diffusion constant for electrons, n_i =density of electrons in the intrinsic regions, L_n =diffusion length for electrons, P =the average doping over a distance of several diffusion lengths from the edge of the depletion layer, β =Boltzman constant at room temperature, and V =the direct current forward bias voltage.

The PIN or horizontal current for $W/2L \gg 1$, where W =space width and L =diffusion length, is as follows:

$$J_H = \frac{2qn_i \sqrt{\mu_n \mu_p}}{L_i} e^{\beta} \frac{(V_1 + V_2)}{2} \quad (2)$$

where μ_n =mobility of electrons, μ_p =mobility of holes, L_i =the diffusion length of electrons in the intrinsic region, V_1 =DC voltage at one end of the intrinsic region, V_2 =DC voltage at the other end of the intrinsic region, the remaining parameters being the same as those indicated in connection with Equation 1.

Taking the ratio of J_H to J_v it can be shown for a β proportion to 40 volts⁻¹ power, D_p proportional to 10 cm.² per sec., n_i proportional 1.5×10^{10} cm.⁻³, $\mu_n = 2\mu_p = 3600$ cm.² per volt second and P proportional to 10^{18} , the PIN junction current is far greater than that of the PN junction. Since the ratio is so large, the vertical current or the current through the NP junction may essentially be neglected. This fact leads to the conclusion that the device current is directly proportional to the junction diameter. This may be further verified by referring to FIGURE 3 wherein the forward current of the device is listed for applied voltages wherein the ratio of the intrinsic region overall width to the electrode width is varied. FIGURE 3 demonstrates that the device forward current is directly proportional to the junction perimeter and not the junction area. Curves 70, 72, 74, and 76 are for different diameters of intrinsic and $N+$ regions, indicated therein. The rounding of the voltage curves in the region of 1.0 volt forward bias is due to the resistive components of the bulk material. That is, to obtain the same device current, the applied voltage of device terminals must be increased to compensate for the voltage drop in the bulk of the diode material.

The reverse recovery time of the device, which is proportional to the depletion capacitance, is improved over conventional devices. It can be shown that the reverse recovery time of the present device is as follows:

$$\text{erf } \sqrt{t/T} = \frac{1}{2 \left(1 + \frac{I_R}{I_F} \right)} \quad (3)$$

where erf =error function, t =storage time, T =lifetime, I_F =forward current, and I_R =reverse current.

The recovery time of simple PN junctions, as indicated in an article entitled "Diode Storage Time Calculations" by M. Klein, IBM Technical Note TN00481, dated Dec. 6, 1960, is as follows:

$$\text{erf } \sqrt{t/T} = \frac{1}{\left(1 + \frac{I_R}{I_F} \right)} \quad (4)$$

Comparing Equation 3 with 4 it is apparent that the device containing the PIN structure is more than twice as fast in recovery as the simple PN diode. Since the majority of the steady state current flows through the PIN junction, the depletion capacitance of the present device is approximately half of that of the regular device.

It would appear that a PN junction in the device is relatively inactive. Its activity, if anything, could be described as unwanted since, due to its highly doped concentration on both sides of the junction, it compromises all of the device capacitance and lowers the device breakdown voltage. One would, therefore, be tempted to conclude that the PN portion of the device should be eliminated and a better device would result. The merits of a PN junction, however, become evident when the forward recovery voltage is examined. Referring to FIGURE 4, devices of two different diameters ($D_1=10$ mils, $D_2=12$ mils) and three different lifetimes ($t_i=12$ nanoseconds, 16 ns., 22 ns.) are indicated. FIGURE 4 shows that the smaller the I region thickness and the larger the junction diameter the smaller will be the forward recovery voltage. The effect of the PIN junction, therefore, becomes apparent. Since the PN junction has no I region, all of the transient currents will flow to the PN junction during the initial signal application. Thus, it is apparent that FIGURE 4 demonstrates that the transient forward current initially flows through the PN junction and as the diode approaches steady state, the PIN junction absorbs more and more of the current capability until all of the current flows through the PIN junction. The PN junction, therefore, provides low forward recovery voltage which is important in high speed switching devices.

It is important that the width of the intrinsic region W to the diffusion length L be less than 1 in order for the effects of the invention to be realized. It can be shown that the voltage across the intrinsic region is as follows:

$$V_I = (\pi/2) \left(\frac{KT}{q} \right) (\mu^*) e^{w/L}$$

$$\mu^* = \frac{\mu_n \mu_p}{(\mu_n + \mu_p)^2}$$

where K =Boltzman constant, T =temperature, q =charge, μ =mobility, μ_p and μ_n are as indicated in Equation 2, w =intrinsic width and L =diffusion length.

For a W/L ratio of 5; $V_I=1.5$ volts. Laboratory measurements, however, show that the voltage drop in the I region is nowhere near 1.5 volts but rather near 0.8 volt. Thus the W/L ratio is less than 1. It is apparent, therefore, that the horizontal current flows immediately to the $P+$ region immediately adjacent the junction 56. This current flow provides a negligible voltage drop. Thus, the W/L is highly instrumental in determining the path of current flow. For a ratio greater than 1, the intrinsic field is sufficiently large to affect the device operation. For a W/L ratio of less than 1, the intrinsic voltage drop is negligible and produces the result of low forward recovery voltage and reverse recovery voltage. The low reverse recovery is accompanied by low depletion capacitance and a linear dependence of the forward current on the diode diameter rather than the diode area. These features make the device an ideal high speed switching element.

Although the device described is a semiconductor diode, it is believed evident that the principles of the invention are applicable to transistors requiring low minority carrier storage as shown in FIGURE 5. In addition, if a subsequent P-type diffusion 70 follows the $N+$ diffusion 54 (which has been used to form the $P+N+$ diode) then a PNP-PNIP transistor can be made. A transistor of this construction would have the following advantages: (a) high base doping-low base resistance, (b) low collector capacitance (I-region), (c) minimal base widening, (d) low lifetime (gold diffusion). Furthermore, by varying the width of the sidewall I-region, the current could be distributed either totally or symmetrically between the two transistor profiles—vertical and horizontal (PNP-PIP).

While the invention has been particularly shown and described with reference to preferred embodiments thereof, it will be understood by those skilled in the art that

various changes in form and details may be made therein without departing from the spirit and scope of the invention.

What is claimed is:

1. A semiconductor device comprising a semiconductor wafer of a first conductivity type, a first semiconductor region of a second conductivity type disposed in the wafer and establishing a first junction, and a second compensated doped region of substantially no conductivity type disposed in the wafer and surrounding the first region and establishing a second junction therewith, said second region bounded by the first conductivity type of the wafer and the second conductivity type of said first region, and wherein the wafer and the first region are heavily doped with an impurity concentration of at least 10^{19} atoms per cubic centimeter.
2. The device of claim 1 further including an ohmic contact covering the first region and extending over onto a portion of the second region.
3. The device of claim 1 wherein said second region defines an intrinsic region comprising impurities of said second conductivity type compensated by about 10^{15} to 10^{17} atoms per cubic centimeter of gold to said substantially no conductivity type.
4. The device of claim 3 further including a contact assembly comprising an insulating film dispersed on a wafer surface and having an opening therein, a first metal disposed in the opening and contacting the first region and extending over a portion of the second region.
5. The device of claim 4 further including successive layers of metals covering the first metal and the insulating film.
6. The device of claim 5 wherein the wafer has an impurity concentration of 10^{19} atoms/cubic centimeter, the first region has an impurity concentration of 10^{21} atoms/cubic centimeter, and the second region has an impurity concentration of 10^{13} atoms/cubic centimeter.
7. A transistor comprising a semiconductor wafer of P type conductivity, an epitaxial layer of N type conductivity grown on a surface of the wafer, a first region of P type conductivity diffused into a portion of the epitaxial layer, a second region of N type conductivity diffused into outer portion of the epitaxial layer to establish an N+ layer spaced from said first region with the remaining portions of said epitaxial layer defined between said first and second region comprising a gold compensated region establishing a substantially intrinsic region defining a third region of substantially no conductivity type, and a P type region diffused into a portion of the N+ region.
8. A semiconductor device comprising a semiconductor substrate of a first conductivity type, a first semiconductor region of a second conductivity type disposed in the wafer and establishing a first junction; and a second region of intrinsic material disposed in said wafer adjacent to and peripherally contiguous with said first region, with said intrinsic region comprising impurities of the second conductivity type substantially compensated to substantially no conductivity type by about 10^{15} to 10^{17} atoms per cubic centimeter of gold.
9. The device of claim 8 including a third diffused region of said first conductivity type spaced from said first region and contiguous with said second region.
10. The device of claim 8 wherein said regions termi-

nate on a common surface and the junction depth of said second region does not exceed the junction depth of said first region.

11. The device of claim 10 including a third diffused region of said first conductivity type spaced from said first region and contiguous with said second region.

12. A semiconductor device comprising a substrate having

- (A) a first semiconductor region of a first conductivity type
  - (a) in said substrate, and
  - (b) spaced from the top surface thereof;
- (B) A second diffused semiconductor region of said first conductivity type
  - (a) contiguous with said first region, and
  - (b) extending therefrom toward said top surface;
- (C) a third region of intrinsic material disposed in said substrate adjacent to and surrounding said second region to establish a junction with said first region, with said intrinsic region comprising
  - (a) a region containing impurities of a second conductivity type substantially compensated by about 10^{15} to 10^{17} atoms per cubic centimeter of gold, and defining
  - (b) a third region of substantially no conductivity type and
  - (c) contiguous with said first and second regions; and
- (D) a fourth diffused semiconductor region of said second conductivity type
  - (a) contiguous with said first and third regions, and
  - (b) spaced from said first region; and
- (E) a fifth diffused semiconductor region of said first conductivity type inset in said fourth region and extending from said surface toward said first region in spaced relationship therewith.

13. The device of claim 12 wherein, relative to said surface, the junction depth of said third region does not exceed the junction depth of said fourth region.

14. The device of claim 12 wherein said second and fourth regions are laterally contiguous with said third region.

15. The device of claim 14 wherein relative to said surface, the junction depth of said third region does not exceed the junction depth of said fourth region.
